UNITED STATES PATENT OFFICE.

LOUIS F. BLUME, OF PITTSFIELD, MASSACHUSETTS, ASSIGNOR TO GENERAL ELECTRIC COMPANY, A CORPORATION OF NEW YORK.

WINDING MACHINE.

Application filed March 26, 1921. Serial No. 455,830.

To all whom it may concern:

Be it known that I, LOUIS F. BLUME, a citizen of the United States, residing at Pittsfield, county of Berkshire, State of Massachusetts, have invented certain new and useful Improvements in Winding Machines, of which the following is a specification.

This invention relates to winding machines, and more particularly to machines for winding coils in flat spirals.

In some types of electrical apparatus, for example transformers, use is made of coils which must withstand a comparatively high potential at its terminals. It is therefore necessary to insulate the layers of conductors from each other and this insulation must be better than that between individual turns, since the electrical potential from layer to layer is proportional to the number of turns in each layer and the potential between each turn. If each layer contains a large number of turns, it is evident that there may be a very high difference of potential existing between adjacent layers, so that a comparatively large amount of insulation is required. Thus in a coil having a definite voltage applied thereto and a definite number of turns, if there be only a small number of layers the entire voltage applied to the terminals is divided only into as small a number of parts as there are layers, and the voltage between one turn and the turn immediately under or over it may reach a correspondingly high value. One way of reducing the voltage between layers is by increasing the number of layers. It is the main object of my invention to increase the number of layers wound in the coil by winding it as a cylindrical body, the first layer being wound in a flat spiral against the end collar of the cylinder in the manner of a clock spring, and the succeeding layers being wound in the same way so that there are a large number of layers extending from one spool flange to the other. Under such circumstances, since less insulation is used between layers, there is a corresponding improvement in the space factor, or the ratio of useful conductor to the entire space occupied by the winding.

Attempts have been made in the past to construct machines for winding the coils with such spirals, but mechanical drawbacks arise, since it is difficult to support those

portions of the coil that are already wound during the winding operation. It is therefore another object of my invention to provide such a machine having few parts and capable of performing the necessary operations. More specifically, one of the objects of my invention is to provide a stationary presser plate or support for the flat spirals as they are wound, whereby they can be more easily retained in place. Other objects and advantages of my invention will become apparent as the description proceeds.

For a better understanding of my invention, attention is directed to the following specification and accompanying drawings, in which Figure 1 is a view in elevation of a complete machine embodying my invention; Fig. 2 is a top plan view thereof; Fig. 3 is a sectional view along the lines 3—3 of Fig. 2; and Fig. 4 is an enlarged sectional detail showing how the turns are guided in the layers.

Referring now more in detail to the drawings, in which like reference characters refer to like parts throughout, the spool body 11 is appropriately supported on a flange member or presser plate 12. This flange or presser plate 12 is mounted for rotation on a shaft 13. The means for rotating this presser plate in the present instance comprises a pulley 14 fastened to shaft 13 and arranged to be driven by any appropriate source of motion, such as the electric motor 15, by means of the belt 16 and pulley 17. A metallic plate 18 is placed directly over the active surface of the presser plate 12 and it is upon this member 18 that the conductor 19 is wound. I provide a table member or support 20 having castors 21 arranged to maintain the pulley 14 with its axis vertical.

One of the most important features of my invention is the provision of a stationary presser plate, against which the layers are successively wound. This presser plate may take the form illustrated in Figs. 1 and 4 at 22 and comprises in this instance an annular shaped member of thin sheet metal, such as copper or steel and having a depending flange 23. This stationary presser plate 22 is provided with a strap member 24 coacting with an upright stud 25 whereby rotation of this presser plate is effectively prevented. However, as the wire is laid in successive layers between the presser plates 12 and 22

- the presser plate 22 rises upwardly as the winding grows. I provide means for supplying a pressure between the two presser plates tending to urge them together. In 5 this instance there are shown weights 26 disposed on the horizontal flange of the stationary presser plate 22. By using the proper amount of weights an appropriate pressure may be provided.
- 10 The flexibility and resilience of the stationary presser plate 22 whereby it may yield to the force exerted on it by the conductors as they are wound, are of great importance, since in this way a fairly uniform 15 pressure may be exerted on the turns, due to weights 26. This is especially necessary when a layer is just being started, since then the entire presser plate if it were not made of flexible material would rest totally on a 20 single turn or a part of a turn. Rendering it flexible will relieve this pressure and will enable one to start the first turn in a layer without difficulty.

In order to form a compact winding 25 whereby the succeeding turns in a layer may be tight one against the other, I provide means whereby the conductor is pulled in while a spiral is wound from the inside to the outside from the spool body 11, and 30 means tending to supply the conductor at a rate faster than needed, while it is wound from the outside to the inside. This latter means is thus so arranged that the first turn of the layer in winding from the outside 35 to the inside is tightly pressed against the depending flange 23, and the succeeding turns are in a similar way pressed against the preceding turns. To secure this result I use a feed for the wire between the presser 40 plates producing an axial thrust along the wire.

The feeding mechanism is shown generally at 27 and comprises a pair of feed rolls 28 arranged for rotation from the shaft 45 13 by means of the pulley 29 located on shaft 13, idler pulleys 30, 31 and 32, belt 40 and pulleys 39. The conductor 19 is arranged to pass between the bite of the feed rolls 28, as clearly shown in Fig. 1. The 50 idler pulley 30 is supported on a block 33 which is held to a supporting member 34 secured to the base 20. The idler pulleys 31 and 32 rotate on the shaft 35 appropriately supported as by straps 36 from the member 33. The feed rolls 28 are securely fastened on shafts 37 and 38, appropriately supported from the member 33. Said shafts 55 carry the smaller pulleys 39, about which passes the belt 40 in the manner clearly shown in Fig. 1.

60 After the conductor passes through the bite of the rolls 28 it passes through a feeding nozzle or tube 41. A long helical spring is used for the body of this nozzle 65 whereby it is rendered flexible and easily

adjusted in curves or straight lines as occasion may demand. The forward end of this spring is supported in a block 42 carried between a pair of swinging arms 43. The front end of the nozzle where the wire 70 passes out between the presser plates is made of a slightly bent tube 44, as clearly shown in Fig. 2. As the spiral grows either from the inside to the outside or vice versa, the swinging frame work comprising members 43 and the support 42 is made to describe a small arc. To urge the swinging frame in the right direction, use is made of a small tension spring 45 which is permanently secured to the upper frame 43 but is 75 detachably secured to either one or the other of the straps 46 supported on a stationary part of the apparatus. In this way the swinging frame may be resiliently urged either in one direction or the other. In lieu 80 of or in addition to this spring arrangement for urging the swinging frame one way or the other, I may provide a guiding heel 47 on the underside of the tube 44. This heel is shown in Fig. 4 and is arranged 85 to be guided by the preceding turn of the layer and thereby to guide the movement of the swinging frame. In this way the gradual movement of the nozzle radially is automatically effected. The upper presser 90 plate 22 is cut away for a short distance 48, as shown in Fig. 2, to allow the nozzle to introduce the wire between the presser plates. The diameters of the various pulleys 95 which serve as elements in the drive for the feed rolls 28 are such that there is always a tendency for the conductor to be fed too fast while the feed is active. This results in an axial thrust of the conductor through the nozzle 41, made use of while winding 100 from the outside to the inside, for pressing the first turn against the flange 23, and succeeding turns against the preceding. The surplus movement is taken care of by the slipping of the belt on the pulleys. The 105 amount of slipping may be regulated by any appropriate means. In the present instance I provide a spring 49 fastened to an adjustable member 50 pivoted to the underside of the support 33, as clearly shown in 110 Fig. 3. By swinging this member 50 in one direction or the other and clamping it in position by means of the wing nut, the tension of the spring 49 may be adjusted. The other end of the spring 49 is fastened to a 115 member 51 pivoted on shaft 35 and arranged to provide a frictional load for shaft 37 which carries the upper feed roll. It is evident that by causing a frictional load to be imposed on this shaft, the force acting 120 axially upon the conductor 19 will be reduced, due to the fact that more of the energy transmitted by belt 40 is used up against friction.

When the layer is wound from the inside 130

to the outside the feed is rendered inoperative as, for example, by removing the belt 40. Furthermore, matters are so arranged that the conductors are pulled between the 5 feed rolls by the rotation of the rotatable presser plate 14. This is effected by mounting the spool or reel 53 which carries the conductor on a shaft 54 and in such a way that there is an opposition to the rotation 10 of the reel 53. This opposition may be due to friction or the action of weights or springs in well understood expedients.

In addition to the provision of an axial thrust on the conductor while it is wound 15 from the outside of the spiral to the inside, I provide appropriate means for taking the load off the feed rolls for pulling the conductor off of the reel 53. To do this I provide a drum 55 rotated by any appropriate means, 20 as by the motor 15; the conductor 19 is wound several times about this drum. If the feed rolls 28 pull this conductor 19 taut enough friction is present between the conductor and the face of the drum 55 so as to 25 cause it to be advanced by the rotation of this drum. This results in slackening the conductor automatically before it reaches the feed roll 28 and relieves the feed roll of the work of pulling the conductor. When the 30 spiral, however, is wound from the inside to the outside, this drum 55 is not used and the conductor 19 is taken off of the drum entirely. Under such circumstances as explained before, an appreciable force opposing 35 the pull on the conductor may be provided to lay the turns tightly against each other.

As the coil is wound layer after layer the presser plate 22 rises vertically. After it 40 has been wound with the required number of layers and turns, the presser plate 22 may be removed entirely from the machine. Belt 40 must of course be taken off of pulley 29 and the frame 23 swung away. The entire 45 coil can then be removed from the rotatable presser plate and a new one started. In starting a new layer, the machine is stopped, the spring 45 adjusted and the belt 40 and drum 54 rendered operative or inoperative 50 as occasion demands.

It is apparent that I have invented an extremely simple and efficient form of apparatus for winding coils in the manner described. While I have shown in the accompanying illustrations the preferred embodiment of my invention, I do not wish to be limited thereto but aim to embrace in the appended claims all modifications falling fairly within the scope of my invention.

60 What I claim as new and desire to secure by Letters Patent of the United States, is:—

1. In a machine for winding coils in flat spirals, a rotatable presser plate, a stationary presser plate, means for urging said

plates together, and means for feeding a conductor between said presser plates. 65

2. In a machine for winding coils in flat spirals, a pair of presser plates between which the spirals are wound, means for rotating one of said plates, and feeding mechanism for the conductor comprising a feed roll, a slipping drive for said roll, and means for opposing the pull on the conductor while it is wound from the inside to the outside. 70

3. In a machine for winding coils in flat 75 spirals, a pair of presser plates between which the spirals are wound, means for rotating one of said plates, and means tending to advance the conductor faster than it is wound while winding from the outside of 80 the spiral to the inside.

4. In a machine for winding coils in flat spirals, a pair of presser plates between which the spirals are wound, means for rotating one of said plates, means for causing 85 the conductor to be pulled against an appreciable opposing force while it is wound from the inside to the outside, and means tending to advance the conductor faster than it is wound while winding from the outside 90 of the spiral to the inside.

5. In a machine for winding coils in flat spirals, a non-rotatable presser plate, a rotating presser plate, a feed roll for the conductor to be wound, and means for driving 95 said roll, said driving means being so proportioned that while effective it tends to rotate the roll at a rate faster than that required to feed the conductor.

6. In a machine for winding coils in flat 100 spirals, a stationary presser plate of thin flexible metal, a rotatable presser plate, and means for urging said plates together.

7. In a machine for winding coils in flat spirals, a stationary yieldable presser plate, a 105 rotatable presser plate, and means for urging said plates together.

8. In a winding machine, a feed roll, a pulley, and driving means for said pulley, arranged so that the material to be wound 110 will be wound tightly upon the pulley whenever the material is pulled taut by the feed roll, whereby said pulley serves to advance the material.

9. In a machine for winding coils in flat 115 spirals, a pair of presser plates, means for urging said presser plates together, a feeding nozzle directing a conductor between the presser plates, and means for urging the conductor forward under axial thrust through 120 said nozzle.

10. In a machine for winding coils in flat spirals, a pair of presser plates, means for urging said plates together, means for feeding a conductor between said plates, a flange 125 on the periphery of one of said plates, supporting the outside of the coil.

11. In a machine for winding coils in flat

spirals, a pair of presser plates, means for urging said presser plates together, a feeding nozzle directing a conductor between the presser plates, means for urging the conductor forward under axial thrust through said nozzle, and a flange at the periphery of one of said plates, supporting the outside of the coil.

12. In a machine for winding coils in flat spirals, a pair of presser plates, means for feeding a conductor between said plates so as to wind said conductor into spirals formed alternately from the inside to the outside and

from the outside to the inside, and means for applying a tension to said conductor when winding from the inside out and for applying an axial thrust to said conductor when winding from the outside in. 15

13. In a machine for winding coils in flat spirals, a pair of presser plates, means for urging said plates together, a feeding nozzle, and a guiding heel carried by said nozzle adapted to rest on a preceding turn. 20

In witness whereof, I have hereunto set my hand this 23rd day of March, 1921.

LOUIS F. BLUME.
